UNITED STATES PATENT OFFICE.

DAVID H. MOSS, OF NEWARK, NEW JERSEY, NICHOLAS J. CELENZA, OF BROOKLYN, NEW YORK, AND WILLIAM H. GERNS, OF EAST ORANGE, NEW JERSEY, ASSIGNORS, BY MESNE ASSIGNMENTS, TO BRANDES LABORATORIES, INC., OF NEWARK, NEW JERSEY, A CORPORATION OF NEW JERSEY.

TERMINAL BLOCK AND CONNECTIONS FOR TELEPHONE RECEIVERS.

Application filed March 20, 1925. Serial No. 17,051.

To all whom it may concern:

Be it known that we, DAVID H. MOSS, NICHOLAS J. CELENZA, and WILLIAM H. GERNS, residing at Newark, in the county of Essex and State of New Jersey, Brooklyn, in the county of Kings and State of New York, and East Orange, in the county of Essex and State of New Jersey, have invented certain new and useful Improvements in a Terminal Block and Connections for Telephone Receivers, of which the following is a specification.

Our invention relates broadly to electromagnetic sound reproducers, and more particularly to connections for telephone headsets.

One of the objects of our invention is to provide a terminal block and connections for telephone receivers in which rigid mechanical connections and good electrical contact may be made between the flexible cords leading to the external electrical circuit, an electrostatic shield surrounding the conductors, and the electromagnets and case of the telephone receivers.

Another object of our invention is to provide a terminal block which may be positioned interiorly of a telephone receiver casing and connections completed with flexible conductors leading to the telephone receivers by a clamping device operative from the exterior of the telephone receiver casing, the clamping device being constructed of a metallic follower plate adapted to be advanced or retracted upon rotatable screws operated from the rear of the telephone receiver.

Still another object of our invention is to provide contact members within the telephone receiver casing and flat terminal devices on the ends of telephone receiver cords with instruck and outstruck projections on the flat terminals arranged to cooperate with outstruck projections on the terminal devices within the telephone receiver casing for rigidly anchoring the flexible conductors within the telephone receiver casing and

maintaining good electrical contact at all times.

Our invention is an improvement upon the invention set forth in application Serial No. 672,949, filed November 5, 1923, filed by Frederick Dietrich, entitled Electrical connections for telephone headsets. We provide a mechanical arrangement of fixed outstruck contacts carried within a terminal block in the telephone receiver casing with a metallic follower plate separated at all times from said fixed contacts by insulation, the follower plate having means whereby it may be advanced in the direction of the fixed outstruck contacts to grip deformed flat terminals against the fixed contacts for mechanically securing the conductors within the telephone receiver casing and complete a substantial electrical contact therewith. The fixed electrical contacts are housed within an insulated terminal block located interiorly of the telephone receiver casing with apertures registering with apertures in one side of the telephone receiver casing in such manner that a plurality of terminals, a pair of which are employed in conducting the telephone currents while a third is employed as a connection for the shield about the telephone conductors may be simultaneously clamped in the terminal block and mechanically locked in position at the same time that good electrical contact is made between circuits interiorly of the telephone receiver and external electrical circuits.

Our invention will be more clearly understood from the following specification by reference to the accompanying drawings forming a part thereof, in which Fig. 1 is a plan view of the telephone receiver casing showing the terminal block of our invention arranged therein; Fig. 2 is a side view of the telephone receiver showing the interior terminals and the entrances in the side wall of the telephone receiver; Fig. 3 is an enlarged view of the terminal block which is mounted within the telephone re-

ceiver; Fig. 4 is a side view of the terminal block; Fig. 5 is a fragmentary view of the terminal block illustrating the metallic follower plate and the insulation member in spaced relation within the terminal block; Fig. 6 is a fragmentary plan view of the terminal block illustrating the follower plate and insulating strip in plan spaced from the terminal block; Fig. 7 is a perspective view of the terminal block and flat terminals which are provided on the extremities of the telephone conductors; Fig. 8 is an enlarged fragmentary section through the terminal block within the telephone receiver casing; Fig. 9 is an end view of one of the flat outstruck and instruck terminal members employed on the extremities of the telephone conductors; Figs. 10 and 11 are plan and side views of the terminals used on the extremities of the telephone cords; Figs. 12, 13 and 14 are views of the outstruck fixed terminals which we provide in the terminal block within the telephone receiver casing; and Fig. 15 is a perspective view of one of the terminals which we provide on the extremity of the telephone cords.

Our invention is particularly applicable to telephone receiver construction where receivers are manufactured on a large production scale. The connecting block and connections which we provide are so securely anchored during the assembly process that good electrical connection may be maintained throughout the life of the telephone receiver. The terminal block and terminals therefore are simple in construction and capable of manufacture inexpensively on a quantity production basis. Our invention has proved successful and efficient in operation.

Referring more particularly to the drawings, reference character 1 designates the telephone receiver casing including therein permanent magnets 2, electromagnets 3 and terminal block 4 secured in position by kidney pieces 5 and 6. The telephone receiver is provided with a cap 7. The terminal block 4 is substantially semi-circular in shape and contains a rectangular recess 8, in the lower portion of which there is positioned a set of fixed outstruck contacts 9, 10 and 11. The contacts 9 and 11 are shaped substantially in the form of right angles and are provided at their central portions with outstruck contacts 9^a, 10^a and 11^a. The fixed contacts are outstruck from the lower side thereof as represented at 11^b in Fig. 14 in such a manner that the upper portions of the contacts are substantially raised forming an obstruction or obstacle over which flat terminals which are projected through apertures 12, 14 and 15 of the terminal block may be hooked and rigidly secured. The terminal block is provided with intermediate portions 16 and 17 which

are apertured at 18 and 19 and provided with upwardly extending guides 16^a and 17^a. Screw members which control the position of the follower plate 20 pass through the apertures 18 and 19 from the exterior of the telephone receiver casing 1 and engage with threads 21 in the follower plate 20. The flexible conductors of the telephone head sets are represented as contained within the casing 22 which is fanned out at 23, 24 and 25. Upon each extremity of these conductors a flat terminal member 26, 27 and 28 is provided. The extremity of the terminal member is provided with a pair of projections represented at 28^b and 28^a which extend along the length of the terminal member 28 substantially at right angles to the line along which the projections 9^a, 10^a and 11^a of the fixed contacts extend. By this arrangement of projections, a lock may be obtained by the abutment of the sets of contacts or the terminal members against the projections and the fixed contacts. After the projections on the terminals which extend into the telephone receiver casing have been hooked over the projections formed on the contacts within the recess 8 of the terminal block, the screws 29 are operated from the exterior of the telephone receiver casing and advance the follower plate 20 in the direction of the recess in the terminal block. Insulated plate 30 having apertures 30^a corresponding to the upwardly extending guides 16^a and 17^a on the terminal block, is disposed between the metallic follower plate 20 and the contact members 26, 27 and 28 preventing short circuit thereof while securing the mechanical strength of the metallic follower plate.

It will be observed that by the arrangement of the projections of the terminal members extending substantially at an angle to the projections on the contacts within the telephone receiver casing we are enabled to anchor the terminal members within the telephone receiver casing and obtain a permanent and substantial electrical contact. By this mechanical arrangement the telephone headsets after they have once passed factory inspection may be depended upon to retain their original mechanical and electrical characteristics.

While we have described our invention in certain particular embodiments, we desire it to be understood that modifications may be made and that we intend no limitations upon the invention other than are imposed by the scope of the appended claims.

What we claim and desire to secure by Letters Patent of the United States is as follows:

1. Connections for electromagnetic sound reproducers comprising in combination a casing, an electromagnetic operating mechanism arranged therein, a terminal block

- including a rectangular recess, a plurality of flat outstruck contact projections within said recess, and a plurality of flat terminal members formed on the extremities of flexible conductors projecting into said terminal block, each of said flat terminal members having outstruck and instruck portions adapted to be locked over the outstruck projections of said flat terminals, and means for clamping said flat terminal members in substantially locked position.
2. Connections for electromagnetic sound reproducers comprising in combination, a casing, an electromagnetic operating mechanism arranged therein, a terminal block including a rectangular recess, a plurality of flat outstruck contact projections within said recess, extending in the direction of said recess, a plurality of flat terminal members formed on the extremity of flexible conductors, projecting into said terminal block, each of said flat terminal members having outstruck and instruck portions extending in the direction of the length of said terminals adapted to be locked over the outstruck projections of said flat terminals in abutment with the outstruck projections on said contacts, and means for clamping said flat terminal members in substantially locked position.
3. Connections for electromagnetic sound reproducers comprising in combination, a casing, an electromagnetic operating mechanism arranged therein, a terminal block including a rectangular recess, a plurality of contacts insulated one from another, each of said contacts having outstruck projections extending up into said rectangular recess aligned in the direction of the longitudinal axis of said recess and substantially in the center thereof, a plurality of flexible conductors, flat terminal members formed on the extremities of said conductors, said flat terminal members having projections extending along the length thereof substantially at right angles to the direction of the projections on said contacts whereby the projections on said terminals may be locked over and abut against the projections on said contacts, and means for clamping said flat terminal members in said locked position.
4. Connections for electromagnetic sound reproducers comprising in combination, a casing, an electromagnetic operating mechanism arranged therein, a terminal block including a rectangular recess, a plurality of flat contacts positioned within said rectangular recess and having upwardly extending projections in the direction of the longitudinal axis of said recess, a plurality of flat contact terminals arranged to extend into said terminal block and into said rectangular recess, each of said contacts having projections extending along the
- length thereof and arranged to form abutment members in cooperation with the upwardly extending projections on said contacts, and means for clamping said flat terminal members in substantially locked position with respect to said contacts.
5. Connections for electromagnetic sound reproducers comprising in combination, a casing, an electromagnetic operating mechanism arranged therein, a terminal block including a rectangular recess, a plurality of contact members positioned within said recess each having a projection extending in a central line along said recess, a plurality of flat terminal members arranged to project into said recess and having projections thereon extending substantially at right angles to said afore-mentioned projections, and means for clamping said terminal members in locked position with the respective projections in abutment for securing a rigid mechanical and good electrical contact between said terminals and said contacts.
6. Connections for electromagnetic sound reproducers comprising in combination, a casing, an electromagnetic operating mechanism arranged therein, a terminal block including a rectangular recess, a plurality of flat contacts disposed within said rectangular recess, outstruck projections on said contacts, a plurality of flat terminal members formed on the extremity of flexible conductors arranged to extend into said terminal block, each of said flat terminal members having projections thereon disposed at right angles to said aforementioned projections on said contacts, and means for clamping said terminals against said contacts whereby the projections on said terminals abut against the projections on said contacts.
7. Connections for electromagnetic sound reproducers comprising in combination, a casing, an electromagnetic operating mechanism arranged therein, a terminal block including a rectangular recess, a plurality of flat contacts positioned within said recess and each having an upwardly extending projection, a plurality of flexible conductors having flat terminal members arranged to extend within said recess, each of said terminal members having projections thereon extending substantially at an angle to the projections on said contacts and means for clamping said terminals against said contacts for securing a rigid mechanical and electrical connection between said terminals and said contacts.
8. Connections for electromagnetic sound reproducers comprising in combination, a casing, an electromagnetic operating mechanism arranged therein, a terminal block including a rectangular recess, a plurality of flat contact members positioned within said recess and each having an upwardly ex-

tending projection, a plurality of flexible conductors adapted to enter said casing, flat terminal members positioned on the extremity of each of said conductors and having projections extending in opposite directions, each substantially at right angles to the projections on said contact members and adapted to abut with the projections on said

contact members, and means for clamping said flat terminal members against said flat contact members for completing the substantial and electrical connection therebetween.
